PIPE TAMPER

James C. Anderson, Highland Park, Ill.

Application November 12, 1934, Serial No. 752,570

18 Claims. (Cl. 131—59)

This invention relates in general to an adjustable tamping device for tobacco pipes and has more particular reference to a pocket article which is used for a pipe tamper.

5 The principal object of the invention is in the provision of an adjustable, lightweight tamping device of metal and the like, which occupies a small space and may be incorporated in a pocket implement such as a knife and is easily adjustable for use as a pipe tamping device.

A further object of the invention is in the provision of a suitable pipe tamper construction which can be incorporated as a part of a pocket implement such as a knife, a file, and the like.

15 A still further object of the invention is in the provision of a pipe tamper which is adjustable from a position parallel with the holder to a position at right angles and at the end thereof.

Other objects of the invention will appear hereinafter.

20 In the accompanying drawing, Fig. 1 is a side elevation of a pipe tamper embodying this invention formed as a part of a knife;

Fig. 2 is a top or edge elevation of the same;

25 Fig. 3 is a sectional view of a pipe tamper mechanism as taken on the line 3—3 of Fig. 1; and

Fig. 4 is a view illustrating the application of the tamper to a pipe.

30 In smoking a pipe it is customary to press down or tamp the ashes and tobacco remaining in the pipe to secure better draft, to burn up the remaining tobacco and to provide additional space for the addition of new tobacco. At times the ashes or pipe is so hot that it would burn the finger, and if the finger is inserted a part of the ashes will adhere to the finger and be withdrawn with it, thereby not only soiling the finger but also resulting in the ashes being spread or wiped usually upon the clothes of the smoker.

40 The present invention provides a simple, practical and easily used implement for accomplishing the tamping operation which may be a separate implement or may be incorporated as a part of a knife and the like, which nearly every

45 pipe smoker uses to clean his pipe at times. This implement comprises a slideable button which is yieldingly held parallel with the side of its supporting handle and is easily movable to a position at right angles and at the end of a supporting handle so that the pipe tamper is easily manipulated with one hand, which makes it an ideal implement for use while reading, driving an automobile, and the like, since it does not require the use of both hands nor any visual attention to 50 the manipulation or adjustment of the tamper

but is effected by one hand only and the sense of touch.

Referring now more particularly to the drawing, this pipe tamper is described as combined with the metal handle of a knife, which is an implement also commonly used by pipe smokers, but the tamper may be a separate implement composed only of a holder and an adjustable tamper as shown.

5 In Figs. 1 and 2 is shown a knife having sides 5 and 6 with a blade 7 pivoted therebetween and connected by a pin 8 at one end the sides held apart by a spacer 9 and a rivet 10 at the other end of the blade, with the sides 5 and 6 extending beyond the spacer 9 and the ends 11 and 12 thereof extending toward each other to form a support for the tamper.

The tamper comprises a head or button 15 preferably of metal and about the width of one side of the knife or holder so that it will lie flatly 20 against the side. In the end of the holder is a slot 16 extending from adjacent the end and over the bent extremity 11 of the holder. A pin 17 secured centrally to the tamper button 15 by riveting the outer end 18 thereof extends through the 25 slot and is provided at the inner end with a washer 19 which has an inner rounded surface 20 and is secured to the end 21 of the pin by riveting or the like. In the inner or under side of the tamper 15 is a recess 22 for seating a 30 washer 23 which bears against the outer face of the side plate 5 or holder and is held in yielding engagement therewith by a coil spring 24 surrounding the pin 17 and located between the washer 23 and the inner side of the recess. 35

This construction causes the tamper button 15 to be held yieldingly against the holder at any position along the slot 16 and the inner washer 20 being rounded at its inner side permits the button to turn partially over the curved outer end 11 of the holder so that if the holder extremity is located substantially at right angles, the extremity 11 will have an inner flat contact surface 25 engaged by the washer 19 and an outer flat contact surface 26 engaged by the washer 23 45 which will hold the button yieldingly at right angles at the end of the holder in tamping position.

To effect the movement of the tamper button from one position to the other it is necessary 50 only to grasp the handle portion of the holder in the fingers or palm of the hand and to slide the button in the slot 16 by engaging it with the thumb or one of the fingers. After a tamping operation is complete the tamper button or head 55

is returned in the same manner to the side of the holder and the operation is so simple that it requires only the sense of touch to change it rapidly and easily from one position to the other. 5 Also in the tamping operation the location of a pipe 30 and its bowl 31 is determined by its position in the mouth of the user and the tamper is easily applied thereto simply by the sense of touch and without any visual attention thereto, 10 thus making the implement an ideal one for use while the smoker is also otherwise occupied.

The extremity 12 of one side of the knife may be used to close the end of the slot 16, thereby preventing the tamper button or head from becoming disengaged from the slot or the slot 16 may be closed at the end just beyond the flat portions 25 and 26 to limit the movement of the tamper button or head 15 in that direction. In the making of knives it is customary to provide 20 a lining 14 usually of thin soft metal such as brass, to which the sides are secured. This tamper may be applied either to a knife or holder structure having the linings 14 extending over the tamper portion as shown in Fig. 2 or the 25 linings may be omitted in the tamper portion as shown in Fig. 3. If this tamper construction is applied to a knife the extension of both sides to form the tamper construction is preferable, but if the tamper is simply applied to a holder having 30 a handle and an end portion at right angles to it, no second or other handle portion is necessary.

I claim:

1. A pipe tamper having a holder, a tamping head, and means for mounting the head on the 35 holder to slide from a position at the side of the holder to a position at the end thereof.

2. A pipe tamper having a holder, a tamping head, and means for yieldingly mounting the head on the holder and slideable from a position 40 along the holder to a position at right angles at the end of the holder.

3. A pipe tamper having a holder with a mounting slot, a tamper head, and means for mounting the head to slide in the slot from a position 45 along the side of the holder to a position at right angles thereto at the end thereof.

4. A pipe tamper having a straight holder with an end at an angle thereto and a slot in the end portion, a tamper head, and means for mounting 50 the head to slide in the slot from a position at the side of the holder to a position at the end thereof at right angles to its side position.

5. A pipe tamper having a holder handle with a curved end portion and a slot in the end portion, a tamper head, and means for yieldingly 55 mounting the head for movement in the slot.

6. A pipe tamper according to claim 5, in which the tamper head has a pin extending through the slot and a washer at the end of the pin, and a 60 spring between the holder and the head to hold it in place in the slot.

7. A pipe tamper according to claim 5, in which the under side of the head has a recess with a pin extending from the head through the slot, a 65 washer at the end of the pin at the other side of the holder, another washer surrounding the pin at the recess side of the holder, and a spring in the recess around the pin and pressing the washer in the recess against the holder.

8. A pipe tamper having a holder with spaced

sides and one turned toward the other at the end, a tamper head, and means for mounting the head in one of the holder sides for slideable movement against the other at the end thereof.

9. A pipe tamper having a holder with spaced 5 sides turned together at the ends and one having a slot therein, a tamper head, and means mounting the head in the slot for movement from a side to an end position.

10. A pipe tamper having a holder with its end 10 turned at a right angle thereto and a slot in the end portion, a tamper head, and means for resiliently mounting the head for movement in the slot and to engage the angled portion thereof to hold the head at right angles to the other portion of 15 the holder.

11. In a pipe tamper according to claim 10, the mounting comprising a pin extending through 20 the slot and a washer at the end of the pin which has a rounded inner surface adapting it to slide freely on the angled portion and to engage the turned portion of the end.

12. In a pipe tamper, a holder having opposite spaced sides turned toward each other at one 25 end and one side and the turned portion having a slot therein, and a tamper head mounted in the slot and movable from a position against the side to a position at right angles thereto at the end.

13. The combination of a holder handle having a bent end with a slot therein, a tamper head, 30 and a yielding mounting therefor including a washer at the side opposite the head with its inner side curved to slide around the bend at the end of the holder.

14. The combination with a holder having 35 spaced sides turned toward each other at one end and a slot in this end of one side, a tamper head, and means mounting the head to slide yieldingly in the slot.

15. The combination with a knife having spaced 40 sides extended at one end, said sides turned toward each other and one of said sides having a slot therein, of a tamper head, and means mounting the head in the slot for moving the head against the side and at an angle to the end 45 thereof.

16. The combination with an implement having parallel sides spaced apart and extended at one end, a tamper head, and means for mounting the head in the said extended portion to slide 50 from a side to an end position.

17. A combined knife and pipe tamper comprising parallel sides in which a blade is mounted the sides extending beyond the blade at one end, and one of the extending sides having a slot 55 therein, a tamper head, and means extending from the head through and beyond the slot and covered by the other side for mounting the head to move against the side and at an angle to the end thereof.

18. A combined knife and pipe tamper having 60 sides in which the knife blade is pivoted, the ends of the side extending beyond the blade when closed and one side including a slotted portion bent at the end, a tamper head, and means yieldingly mounting the head in the slot for movement against the last mentioned side and in the bent portion at right angles to the side.
